UNITED STATES PATENT OFFICE.

RICHARD H. TYNER, OF CINCINNATI, OHIO.

MARKING, LISTING, AND ASSORTING BOOTH.

1,349,699.

Specification of Letters Patent. Patented Aug. 17, 1920.

Application filed October 28, 1919. Serial No. 334,057.

To all whom it may concern:

Be it known that I, RICHARD H. TYNER, a citizen of the United States, and a resident of Cincinnati, in the county of Hamilton and State of Ohio, have invented a certain new and useful Marking, Listing, and Assorting Booth, of which the following is a specification.

It will be understood that in the handling 10 of articles to be laundried in laundries, it has been found difficult to work out an efficient and economical system of handling the laundry from the time that it reaches the laundry in the form of bundles until it has 15 been marked, listed, counted and assorted, so that it is ready to be placed in the various washing machines handling the different classes of goods, which are to be washed.

It will be noticed that it is essential that 20 each piece of the laundry be permanently and legibly marked as soon as possible after it has been taken from the original bundle, in order that even though misplaced, no pieces should be lost.

25 After the laundry is marked, it is then essential that an accurate count of the goods in the bundles be made, and preferably that the count include the number of pieces in each class of laundry articles, as well as the 30 total number of pieces in the bundle. Next it is important that the laundry be assorted into classes, so that similar articles requiring similar methods of washing should be placed together. Considerable difficulty has 35 been experienced in the past in the handling of the laundry through these various operations, due to the mixing of the pieces of one bundle with those of another, improper marking, failure to accurately list and count 40 the number of pieces in each class of articles and the total number of pieces in a bundle, and from the loss of pieces due to ineffective safe-guards against the pieces being carried away or dropped.

45 In order to meet the requirements of a laundry and to most efficiently handle the necessary processes in connection with the progress of the laundry from the time the bundles are unwrapped until the pieces are 50 classified for washing in the various washing machines, I have devised my improved laundry booth to thereby efficiently solve the problems.

In view of the problems mentioned, the

objects of my invention may be stated as 55 follows: to provide a booth within which the operator may be segregated from the rest of the employees, so that the operator's attention may not be divided, and so that there will be no place into which the pieces of 60 laundry may be dropped or otherwise misplaced, and thereby lost or separated from the rest of the pieces of the bundle.

A further object of my invention is to 65 provide such a booth, wherein all the necessary operations may be conveniently performed by a single operator to thereby fix the responsibility for errors, and at the same time eliminate the possibility as far as possible of errors.

70 A further object is to provide a booth, which is substantially rectangular and enclosed on three sides, but which permits sufficient light for the various operations to enter the booth, no matter which way the light in 75 the building may come from.

75 A further object of my invention is to provide a shelf outside the booth adapted to have bundles placed thereon, which are to be removed, listed, and assorted, so that the 80 effort of the operator in moving the bundles into the booth one at a time may be limited to the effort required to pull these bundles laterally along a smooth shelf, thereby eliminating physical effort as far as possible.

85 A further object of my invention is to provide within the booth, shelves, tables, work-boxes and so forth, which are arranged below the level of the receiving shelf, and at exactly the right height for the convenience of the operator in performing her various duties, and to so arrange the shelves, work-benches, machines and so forth, so that they are most conveniently placed for instant access.

90 With these and other objects in view, my invention consists in the construction, arrangement and combination of the various parts of the device, whereby the objects contemplated are attained, as hereinafter more 100 fully set forth, pointed out in my claims, and illustrated in the accompanying drawings, in which:

105 Figure 1 shows a perspective view of my improved booth, the operating machines not being therein shown, in order to more clearly illustrate the construction of the booth.

Fig. 2 is a longitudinal, vertical, sectional

view through the booth, the position of the various machines being illustrated in dotted lines.

Fig. 3 is a similar view, showing the other 5 side of the booth.

Fig. 4 is an enlarged, detail view of the hanging device for the assorted clothes.

Fig. 5 is a top or plan view, illustrating the construction of these devices; and

10 Fig. 6 shows an enlarged elevation of the hanging devices.

Referring to the accompanying drawings, I have used the reference numeral 10 to indicate generally a substantially rectangular 15 base adapted to support my booth, and thereby make it an independent unit, capable of being moved to the most advantageous position in the laundry.

Fixed to the base 10, adjacent to the 20 corners thereof are spaced, vertical uprights 11 and 12, which are adapted to form the four corners of my booth. The forward uprights 11 terminate about breast-high and have elbows 13 secured thereto, which receive 25 laterally extending brackets or arms 14.

The arms 14 support a shelf 15, which is preferably composed of wood or light sheet metal, and highly polished on its upper surface to press a minimum resistance to 30 sliding laundry bundles over it.

The space between the corner posts 11 is filled by a wire grating 16 adapted to permit light to pass therethrough, but of sufficiently small mesh to prevent laundry pieces from 35 being accidentally pushed therethrough.

A similar frame 17, carrying wire lattice, extends between each of the posts 11 and the adjacent posts 12.

It must be seen that the back end of the 40 booth is left open for a purpose which will hereinafter appear.

Brass rods 18 extend between the posts 12 and 11 on the sides and front about waist-high, and help to render the structure rigid.

45 Extended upwardly from the side brass members 18 about half way between their ends, are metal posts 19, which are connected at their upper ends by a transverse rod 20. A similar transverse rod 20 connects the upper end of the post 12.

Extending between the posts 19 and the posts 12 near their upper ends are side brass members 21. Between the brass members 21 and the brass members 18 is extending 55 siding of comparatively thin wood or light weight sheet metal for a purpose which will hereinafter be set forth.

Extended forwardly from the post 19 and upwardly from the brass 18 are plate glass 60 side members, which are suitably secured to the braces and posts mentioned, thereby forming a transparent siding for a portion of the booth adapted to admit light, but to prevent laundry articles or pieces from being 65 pushed therethrough.

At one side of the booth, a shelf is extended for the entire length of the side and disposed at a convenient height for the operator. This shelf comprises end sections 22 and 23 between which is an open top workbox 24. The rear edge of this shelf is supported on the side brace member 18 adjacent thereto, and the forward edge is supported by posts 25 and 26.

The shelf portion 22 is adapted to support 75 a listing, printing and counting machine, which is indicated by the dotted lines 26^a, and which prints a list of the articles in a bundle according to classes totaling the articles of each class and the total number 80 of articles.

The shelf 23 is intended to support a marking machine, indicated by the dotted lines 27, which is not described in detail, but is intended to imprint upon a customer's 85 laundry articles, a distinctive mark, whereby they may be reassorted, after being washed, into bundles containing all the articles for each customer.

It will be noted that the marking machine 90 is placed at the right hand of the work box 24, which is a box, the upper edges of which are flush with the shelves 22 and 23, and which is adapted to receive a customer's bundle, when it is removed by the operator 95 from the shelf 15. The bundle may then be torn open or unwrapped, the paper thereon thrown outside the booth, and the articles in the bundle will be left loose within the workbox 24.

On the other side of the booth at the forward corner, is a comparatively small shelf 28, supported by the adjacent portions of the braces 18, in position aligned horizontally with the shelves 22 and 23. A space is provided between the adjacent edges of the shelves 23 and 28, so that the operator may conveniently step up to the shelf 15, when she desires to remove a bundle from the latter to place it in the work box 24.

The inner corner of the shelf 28 is supported by a post 29, which is similar in design to the remaining supporting posts of the booth. Mounted on the shelf 28 is a tag sewing machine, indicated by the dotted lines 30 in Fig. 3.

It will be understood without description of the detail construction of this machine, that it is intended to have a roll of tape thereon, which is cut by suitable mechanism on the sewing machine into lengths for laundry tags, and then sewed to laundry articles, so that the marks made by the marking machine 27 may be impressed upon the tag, instead of on the article direct.

It will be understood that there are a definite number of laundry articles, which can not or should not be marked with an impression from a marking machine, as the mark if affixed directly into the goods of 130

the article, would render the article unsightly. In this class of articles are tablecloths, handkerchiefs, and other garments or articles wherein the entire surface of the article may be exposed to view, so that the mark would render it unsightly.

The side or siding 31 adjacent to the shelf 28 is designed to receive columns of laundry hooks, which are somewhat incompletely illustrated in Fig. 3, and illustrated more fully and in detail in Figs. 4, 5, and 6. These laundry hooks are mounted in columns on a sheet metal back, which is formed by corrugating the sheet metal back-
15 ing vertically to form a plurality of outwardly opening channels 32, having side walls 33. The hooks are pivotally mounted in these side walls and are two-piece devices, comprising a loop of wire 34, having its ends bent to extend into the side walls 33, whereby the outer end of the loop 34 may be permitted to swing in a vertical plane. The end of the loop 34 is bent down to form a tab at 35. The second part of the hook 20 devices comprises a loop 36, which has its ends similarly turned out at 37 to be pivotally received in the side walls 33 in position spaced downwardly from the pivotal points or ends from the loops 34, and has formed therein intermediate of its ends an eye 38 at either side, designed to be slidably mounted upon the sides of the loop 34. The 25 end of the loop 36 is also bent down to form a tab 39.

35 From the construction of the parts just described, it will be seen that if the ends of the hooks are moved upwardly, then the swinging of the hooks upon the spaced pivoted points will tend to separate the tabs 35 and 39, as is indicated in Fig. 4 by the dotted lines.

When an article is designed to be secured in one of these hook members, the article is grasped in the hand in such position, 40 that as the hook members are swung from a substantially vertical position down to a horizontal position, then the approaching tabs 35 and 39 will grip the article or garment between them, so that the weight of 45 the garment will tend to pull downwardly on the hooks, thereby forcing the tabs 35 and 39 together, and making the gripping force of these tabs automatically proportionate to the weight of the garment. When 50 it is desired to release all of the garments upon a given column of hooks, the hand is moved upwardly along one side of the column of hooks to thereby bring the thumb or a finger in contact with some portion of the 55 hooks, successively in the column, which raises the outer end of the hooks, spreads the tabs 34 and 39 and thereby permits the garments upon these hooks to fall down. 60 These garments may either be grasped as 65 they fall by the hand of the operator and

thrown into a suitable receptacle disposed at the open rear end of the booth, or, if desired, a receptacle may be placed below the hook rack to receive the garments.

An advantage of my improved construction resides in the fact that I have provided a booth, which separates the operator from the remaining space of the room within which the booth is placed, so that the danger that articles will be lost is substantially 70 eliminated. The operator's attention is not so readily distracted from the work, and the possibility of errors is therefore naturally lessened.

The various shelves, rack and work box 80 are so placed, as to be most convenient for the use of the operator in the various operations which must be performed, if laundry articles are to be unmistakably and accurately marked, counted, listed and assorted 85 or classified.

It will be noted that the work receiving shelf 15 is located outside of the booth, so that new bundles to be operated upon may be placed there from time to time without 90 in any way interfering with the work of the operator. Further, the parts are so arranged, that it is perfectly convenient for the operator to work on but one bundle at a time, thereby substantially eliminating 95 danger of mixing different customers' articles and the various machines for accomplishing the necessary operations may be placed in the positions in which they will be most convenient for the respective operations. 100

For instance, the marking machine, which is the most difficult of operations, and which requires both hands for operating is placed directly to the right of the operator when 105 she picks up an article from an unwrapped bundle from the work box for marking. This operation must or should be performed first and the machine for performing it should therefore be arranged most conveniently for the operator's use, as handling unmarked articles, has a natural tendency to allow errors, and consequently loss of the articles. 110

Next the counting and listing machine is 115 placed to the left of the operator, directly at one side of the work box, so that the articles may first be marked, then listed without the operator moving her feet before said articles are hung upon the hooks of the 120 assorting rack.

The next most natural motion of the operator is to turn around to the right, so that the next most important process is performed in that position, which consists of 125 placing the articles upon the assorting hooks, which are disposed on the opposite side of the booth from the work box.

There are comparatively few articles 130 which must be taped, so that the tape may

receive the mark instead of the article, so that the least important operation is placed in the least accessible position in the booth.

In this connection, it may be mentioned that for moving laundry articles in quantities over the floor from place to place for different operations, it is customary to provide large baskets, which are mounted upon caster wheels and it is intended that such a basket or baskets should be readily available, so that one may be moved up to the rear side of my improved booth and close the rear side, and at the same time be a convenient means for carrying away the assorted, marked and listed articles.

Some changes may be made in the arrangements and construction of the various parts of my improved device without departing from the essential features and purposes 20 of my invention, and it is my intention to cover by my claims any modified forms of structure or use of mechanical equivalents, which may come within their reasonable scope.

25 I claim as my invention :

1. In a laundry marking, counting, listing and assorting booth, a base, a substantially rectangular booth open at one end, a shelf disposed substantially breast-high and 30 extending outwardly from the booth at the end opposite the open end, a work box disposed intermediate of the ends of one side

with its upper edges disposed substantially waist-high, machine supporting shelves at either end of the work box, a third machine 35 supporting shelf disposed in the end adjacent to the first described shelf and the side opposite the work box, and a hook rack disposed on the second side of the booth adjacent to the open end thereof.

40 2. In a booth for marking, enumerating and assorting laundry, a substantially rectangular base, posts extended upwardly therefrom adjacent to each corner, transparent closure members extended between said 45 posts on the sides, and at one end a shelf extending laterally from the booth at the closed end adapted to receive unopened bundles of laundry, a work box disposed intermediate of the ends of one side of the 50 booth adapted to receive the bundles from the bundle receiving shelf one at a time, a shelf at the right-hand end of the work box adapted to receive a marking machine, a shelf at the left-hand end of the work box 55 adapted to receive a counting and listing machine, a shelf adjacent to the bundle receiving shelf, and the side opposite the work box adapted to receive a sewing and taping machine, and a rack disposed on the last described side adjacent to the open end of the 60 booth adapted to receive assorting hooks.

Des Moines, Iowa, September 30, 1919.
RICHARD H. TYNER.
